UNITED STATES PATENT OFFICE.

LOUIS T. MEDHOLDT, OF ROCKFORD, ILLINOIS, ASSIGNOR TO MATTISON MACHINE WORKS, OF ROCKFORD, ILLINOIS, A CORPORATION OF ILLINOIS.

CUTTER HEAD AND KNIFE.

Application filed March 11, 1925. Serial No. 14,595.

This invention relates to cutter heads such as are used in molders and other wood working machines wherein a flat or contoured surface is imparted to boards and strips fed through the machine. Such a cutter head is usually provided with a plurality of knives.

These knives are beveled in various ways for various kinds and conditions of wood. Sometimes they are beveled only on the rear side, to provide clearance. In some instances, the knives are beveled only on the front or cutting side; and in other cases they may be given both a cutting bevel and a clearance bevel. These bevels may be from 1° to 30°.

In order that the corresponding cutting edges of all the knives shall pass through precisely the same orbit and thus operate equally upon the work and so produce the desired smoothness, it is necessary, after securing the knives in the cutter head as nearly in the correct position as possible, to subject the knives to a so-called "truing" or "jointing" operation while the cutter head is rotating at full speed. The truing or jointing operation consists in bringing a suitable abrasive element in contact with the knives as they are revolving at full speed. As a result of this operation the cutting edges of all the knives are ground off slightly until corresponding edges of all the knives travel at the same distance from the axis of the cutter head. The jointing operation changes the bevel of the cutting edge to approximately 45°. The narrow beveled surface thus produced at the edge of the knife by the jointing is termed the "heel". When as a result of repeated truing or jointing, the heel attains a width of approximately one-thirty-second of an inch, the knives must, in most cases, be removed from the cutter head and reground to restore the original clearance or cutting bevel and thus remove the heel. After the knives have been resharpened by the above or any other suitable method, they are again secured in the cutter head as accurately as practicable, and again trued or jointed as above described.

To supplement the bolts ordinarily employed in securing cutter knives in place in the cutter head, one side of the knife is sometimes provided with serrations to coact with a similarly serrated surface on the cutter head or the securing element. It will

be apparent that in mounting a set of such serrated knives in the cutter head it is difficult, if not impossible, to position all the knives with their cutting edges projecting outwardly to the same extent, and consequently the jointing may produce an excessively large heel upon one or more of the knives, the effect of which is to produce a non-uniform surface on the finished work. Hence the removal of such knife or knives from the cutter head for grinding to a new clearance or cutting bevel will soon become necessary.

Among the salient objects of this invention are to produce a form of cutter knife in which the heel shall never exceed the maximum width which can be tolerated, and to render possible the use of expensive high-speed steels or alloys without excessive cost. These objects I attain by means of a knife consisting of or comprising a thin cutting blade preferably of high-speed steel properly backed up by less expensive metal, as by securing the cutting blade between two blades of ordinary tool steel, the thickness of the cutting blade being determined by the maximum width of heel which can be successfully run on the cutter, and said blade being so secured between the other two blades that it may be advanced from time to time to compensate for wear and repeated truing or jointing until the cutter is worn out.

In the accompanying drawings, Figures 1 and 2 are end views of two forms of cutter heads provided with knives embodying the features of my invention.

Fig. 3 is a perspective view of one of the improved knives.

Fig. 4 is a longitudinal sectional view of the knife shown in Fig. 3.

Fig. 5 is another form of the improved knife.

Fig. 6 is an end view of a cutter head in which the knife shown in Fig. 5 may be employed.

Fig. 7 is a fragmental elevation of the cutter head shown in Fig. 6.

Fig. 8 is a fragmentary sectional view showing a pair of gibs supporting the blade in a plain cylinder, the gibs being contoured to provide the backing for the blade.

Referring first to the form of knife shown in Figs. 3 and 4.

Said knife comprises a cutting blade 1' of

high-speed steel or other suitable material and two supporting blades 2 and 3 of less expensive metal, the blade 1 being secured between the blades 2 and 3 by suitable means, as, for example, a screw 4. The edge of the cutting blade may be straight or of any desired contour. The adjacent ends of the supporting blades 2 and 3 are generally similar in form to the edge of the blade 1. The supporting blades 2 and 3 are beveled to provide the necessary clearance. The blade 1 projects beyond the blades 2 and 3 a suitable distance, say, one-sixteenth of an inch. The blades 2 and 3 extend near enough to the cutting edge of the blade 1 to support said blade 1 effectively during the cutting operation.

Cutter-head knives constructed in accordance with the method disclosed in Figs. 3 and 4 may be used in connection with cutter heads of various forms. In Fig. 1 I have shown a cylindrical cutter head A and in Fig. 2 a cutter head B of rectangular cross-section, both adapted to receive knives embodying the present invention.

Most manufacturers are equipped with cutter heads in which the knives are secured in place by means of bolts *a* extending through open-end slots in the knives. The knife shown in Figs. 3 and 4 is provided with a slot 5 to receive such a bolt.

In Figs. 6 and 7 I have shown a cutter head C of the type wherein the cutting element is secured within a slot in the body of the cutter head. Inasmuch as with a cutter head of this type, the cutting blade may be effectively supported without the use of blades such as those indicated at 2 and 3, I have shown a knife 7 in the form of a thin blade of high-speed steel. The cutter-head C is provided with a suitable number of slots 8 of a width corresponding to the thickness of the cutting blade 7. The latter is secured in place by means of a single gib 9 secured in a recess 10 at the forward side of the blade. The head is contoured to correspond generally to the contour of the cutting blade 7.

In Fig. 8 I have shown a cutter head D similar to the head C, but in this instance the body of the head is made plain and two blade supporting gibs 11 and 12 are provided. The outer edge portions of these gibs project beyond the periphery of the body and are contoured so as to provide the necessary backing for the blade adjacent its cutting edge.

The thickness of the cutting element 1 or 7 is determined by the maximum width of heel that can be successfully run on a cutter, and in most instances would be approximately one thirty-second of an inch.

By means of the construction herein shown, it is unnecessary to remove the knives for grinding. When the cutting blades 1 or

7 require resharpening they are subjected to the truing or jointing operation, the cutter head being afterward adjusted toward the work to the necessary extent. When as a result of repeated truing, the cutting edges of the blades 1 and 7 approach too close to the supporting blades 2 and 3 or gibs 11 and 12, (or to the body of the cutter head, in the form shown in Fig. 6), the cutting blades are loosened and adjusted outwardly to a suitable extent.

By reason of the small amount of high-speed steel employed, the first cost of a knife embodying the present invention is less than that of a cutter knife of the prior art. By obviating the necessity of removing the knives for grinding, I effect an important saving in time. This saving is particularly great when serrated knives are used, because of the difficulty of accurately positioning such knives in the cutter head.

It will be observed that the use of the thin cutting blade is rendered feasible by the provision in each instance of a backing for the blade adapted to support it adjacent the cutting edge. When the cutting edge is of a special contour, as is usually the case, the outer edge or face of the backing provided is made of similar contour so as to support the blade uniformly along its cutting edge. The supporting blades such as shown in Figs. 3 and 4, or the gibs 11 and 12, such as shown in Fig. 8 are especially suitable for relatively small manufacturers where frequent changes in the style or form of cutter must be made. In the case, however, of large manufacturers where a particular form or style of cutter is employed over long periods of time, in large quantity production, the body of the cutter head is preferably made of special contour to provide the necessary backing as shown in Fig. 6.

It will be apparent that due to the extreme lightness of the cutter blades, a measurable variation in the dimensions of a group of blades used in a cutter head will not seriously disturb the dynamic balance of the head.

It will also be apparent that the use of such thin blades will provide a cutter head in which the blades all have the same amount of heel and which, therefore, will produce finished work having a uniform surface.

I claim as my invention:

1. A cutting blade for the rotary cutter heads of molders and other wood-cutting machines consisting of a thin blade of metal of a thickness not exceeding the maximum amount of heel that can be tolerated.

2. A cutting blade for the rotary cutter heads of molders and other wood-cutting machines consisting of a thin blade of metal of a thickness not exceeding the maximum amount of heel that can be tolerated, and two supporting blades, one on each side of

the cutting blade, all of said blades being rigidly and detachably connected together, the cutting edge of the cutting blade projecting a slight distance beyond the supporting blades and the latter being beveled at opposite sides of the cutting blade to provide clearance.

3. A rotary cutter head for molders and other wood working machines having a relatively thin cutting blade of a thickness not exceeding the maximum amount of heel that can be tolerated, and a pair of supporting members for the blade one on each side thereof, the cutting edge of the blade having a contour such that a plurality of points therein are variously located with respect to the axis of the cutter, and the outer edges of the supporting members being of similar contour but spaced a slight distance inwardly from the cutting edge of the blade.

4. A cutter head for molders and other wood working machines having a thin blade of a thickness not exceeding the maximum amount of heel that can be tolerated, and

a backing for said blade, the cutting edge of the blade being of a contour such that various points therein are located varying distances from the axis and said backing having a similar contour whereby to support the blade adjacent its cutting edge throughout the length thereof.

5. The combination of a cutting blade for molders and other wood working machines, made from a thin piece of metal and having a cutting edge contoured to produce cuts of varying depth, and a rigid backing member for the blade adapted to be secured with the blade in a cutter head and having its outer edge of a contour conforming to the contour of the cutting edge of the blade, said outer edge of the backing member being disposed adjacent the cutting edge of the blade so as to prevent the latter from yielding in the cutting operation.

In testimony whereof, I have hereunto affixed my signature.

LOUIS T. MEDHOLDT.
